(57) **CLAIM**

The ornamental design for a support for cutting tool, as shown and described.

DESCRIPTION

FIG. 1 is a top view of the support for cutting tool.

FIG. 2 is a bottom view thereof.

FIG. 3 is a side view thereof.

FIG. 4 is an opposite side view thereof.

FIG. 5 is a front view thereof.

FIG. 6 is a rear view thereof; and,

FIG. 7 is a top perspective view thereof.

The broken lines in FIG. 2 illustrate features of the support for cutting tool that form no part of the claim.
